(57) **CLAIM**

The ornamental design for packaging for a ceiling fan motor, as shown and described.

DESCRIPTION

FIG. 1 is a top perspective view of the packaging for a ceiling fan motor showing my design;

FIG. 2 is a front elevational view thereof;

FIG. 3 is a top plan view thereof;

FIG. 4 is a side elevational view thereof;

FIG. 5 is a side elevational view thereof;

FIG. 6 is a back elevational view thereof; and,

FIG. 7 is a bottom plan view thereof.

Any broken line illustration of environmental structure in the drawings is not part of the design sought to be patented.
